US0D1059193S

(12) **United States Design Patent** (10) Patent No.: **US D1,059,193 S**
(45) Date of Patent: ** Jan. 28, 2025

(54) **WATER TANK DETECTION DEVICE**

(71) Applicant: **LIH YANN INDUSTRIAL CO., LTD.**,
Taichung (TW)

(72) Inventor: **Po-Lin Liao**, Taichung (TW)

(73) Assignee: **LIH YANN INDUSTRIAL CO., LTD.**,
Taichung (TW)

(**) Term: **15 Years**

(21) Appl. No.: **29/809,966**

(22) Filed: **Sep. 30, 2021**

(51) LOC (15) Cl. **10-04**
(52) U.S. Cl.

CLAIM

The ornamental design for a water tank detection device as shown and described.

DESCRIPTION

FIG. 1 is a top, front, and right perspective view of a water tank detection device showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof; and,

FIG. 7 is a bottom plan view thereof.

The broken lines in the drawings illustrate portions of the water tank detection device which form no part of the claimed design.

1 Claim, 7 Drawing Sheets
